UNITED STATES PATENT OFFICE

2,519,645

GUTTER SIDE WALL CLEANER
FOR DAIRY BARN

Charles Andrew Gilbert, Evansville, Wis.

Application June 2, 1947, Serial No. 751,863

3 Claims. (Cl. 15—236)

1

The present invention relates to tools, implements and devices which are used for dislodging incrustated deposits from surfaces of collection and drainage gutters of types commonly used in dairy barns and the like.

Modern dairy barns are constructed with disposal gutters, one on each side of the barn, where manure and other waste matter accumulates for satisfactory drainage, handling and practical disposition. Various milk associations require that such gutters be kept clean and free of waste materials and manure. True, cleaning the bottom of the gutter presents no particular problem. However, when ordinary tools and implements are used to clean the sidewalls of the gutter, considerable chopping and scraping is necessary to remove the dried manure, and despite such efforts the gutter is usually not satisfactorily cleaned.

The primary object of the invention is to enable the user to aptly clean both vertical sidewalls of a gutter in one quick, easy operation, and to clean them thoroughly and well.

Another object of the invention is to provide a device of the class described which is such in construction and style that same may be readily handled by a user and this in a manner to effectively and appropriately condition the gutter for sanitary and acceptable usage.

Although it is an object of the invention to generally, structurally and otherwise improve upon known devices and implements, I know of no particular device which suitably accomplishes the ends sought. However, it is an object of the invention to improve upon any known devices for the same purpose, this by providing a simple and practical structural adaptation which is characterized by a handle equipped frame structure which may be maneuvered along the gutter, the same embodying vertical plates or blades having cutting edges to engage the vertical sidewalls of the gutter in scraping relation, whereby to insure effective and adequate results at all times.

Other objects and advantages of the invention will become more readily apparent from the following description and the accompanying drawings.

In the drawings, wherein like numerals are employed to designate like parts throughout the views:

Figure 1 is a fragmentary perspective view showing a portion of a conventional refuse accumulation and drainage gutter of the type under consideration and illustrating the im-

2

proved cleaning and scraping device in use in association therewith;

Figure 2 is a view with parts in section and elevation, which view brings out the details of construction;

Figure 3 is a cross section, on an enlarged scale, which is taken on the plane of the line 3—3 of Figure 2, looking in the direction of the arrows; and,

Figure 4 is a horizontal fragmentary section on the line 4—4 of Figure 2.

Referring now to the drawings by distinguishing reference characters the gutter is denoted as an entity by the reference letter G the same having the usual horizontal bottom B and vertical parallel sidewalls W.

The improved gutter cleaning and scraping device comprises a substantially T-shaped frame which is denoted as a unit by the numeral 6.

The reach or handle portion of the frame is a hollow pipe or the like 7, this being secured to a socket 8 on the central portion of the cross head 9. The cross head is also tubular in construction and therefore functions as a cylinder. As shown in Figure 2 it is provided internally and in its central region with an expansion type coiled thrust spring 10 which bears against the inner ends of duplicate projectible and retractable plunger rods 11 and 12. These are of duplicate construction and a description of one will suffice for both. Each rod is flattened at its outer end as at 13 and is then cut transversely and straight across as at 14. This especially cut end is hingedly mounted as at 15 between a pair of ears or lugs 16 on a co-acting vertical scraper plate. The plate is denoted at 17 and has a beveled edge 18 which constitutes a scraping blade. The plate is tilted in respect to the adjacent wall so that only the cutting edge "knives into" and presses directly against the wall surface. The numeral 19 designates an appropriate hand grip which is connected to the handle member 7 whereas the numerals 20 designate diagonal braces which connect with the handle 7 at the inner adjacent ends and have their outer ends welded or otherwise secured as at 21 to the end portions of the cylinder 9. The portions of the cylinder intermediate the central and end portions are provided, on top and bottom sides, with longitudinal diametrically opposite pairs of slots 22, said slots forming keyways for insertable and removable keying pins 23 carried by each of the plunger rods 11 and 12.

The slots are partially covered by pairs of diametrically opposite arcuate shields 24. The com-

plete inner end portions of all slots are covered by the shields whereas the extreme outer end portions of all slots project slightly beyond the adjacent ends of the shields. These are access holes which serve to permit the insertable and removable keying pins 23 to be removed and inserted. This is necessary in assembling the plunger rods and just sufficient clearance of slots is left for the intended purpose. The main portions of the slots being covered, extraneous matter from the gutter is not fed into the cylinder and spring to interfere with operation of the spring or rods.

It is obvious that in using the device the spring projected and pressed cutting and scraping blades and plates are applied to the surfaces of the vertical walls as shown in the drawings. Then the device is pushed along the gutter in obvious fashion using the handle means for such purposes. The spring pressure maintains the cutting blades in effective yieldable contact with the wall surfaces and hence the cleaning results are effective and reliable.

The advantage of cleaning the sidewalls of the gutter with the invention is that it can be done very quickly and very easily and by its use the gutter sidewalls are cleaned very thoroughly. With the continued use of the invention, the gutter sidewalls of the dairy barn can be maintained free of dirt and waste with a minimum of time. The cleaner can be used for gutters varying in size from 14 1/4" to 17" in width. The cutters can also be made in various lengths so that the invention can be used regardless of the depth of the gutter sidewalls.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

What I claim is:

1. In a gutter cleaning and scraping device of the class described, an elongated horizontal tube constituting a cylinder, the portions of said tube intermediate the center and ends thereof being provided with elongated diametrically opposite pairs of slots, said slots forming keyways, rods fitting telescopically and slidably in the end portions of said tubes, a coiled spring in said tube interposed between the inner ends of the rods for forcing the outer ends of said rods outwardly and beyond the outer ends of said tube, said rods being provided with insertable and removable keying pins, said pins being slidable in said slots, a handle attached at right-angles to the central portion of said tube and including handle bars at its operating end and vertical wall contacting and scraping plates operatively mounted on the outer ends of said rods.

2. In a gutter cleaning and scraping device of the class described, an elongated horizontal tube constituting a cylinder, the portions of said tube intermediate the center and ends thereof being provided with elongated diametrically opposite pairs of slots, said slots forming keyways, rods slidably in the end portions of said tubes, a coiled spring in said tube interposed between the inner ends of the rods for forcing the outer ends of said rods outwardly and beyond the outer ends of said tube, said rods being provided with keying pins, said pins being slidable in said slots, a handle attached to the central portion of said tube and including handle bars at its operating end, rectangular plates hingedly connected to the outer projecting ends of said rods, each plate having one edge beveled and sharpened to provide a scraping edge, the outer side faces of the respective plates being disposed in forwardly diverging relationship to space the said outer side faces thereof away from the surfaces of the vertical walls of the gutter when in use.

3. In a gutter cleaning and scraping device of the class described, horizontal tube constituting a cylinder, the portions of said tube intermediate the center and ends thereof being provided with elongated diametrically opposite pairs of slots, said slots forming keyways, rods slidably in the end portions of said tube, a coiled spring in said tube interposed between the inner ends of the rods for forcing the outer ends of said rods outwardly and beyond the outer ends of said tube, said rods being provided with keying pins, said pins being slidable in said slots, a handle attached to the central portion of said tube and including handle bars at its operating end, rectangular plates hingedly connected to the outer projecting ends of said rods, each plate having one edge beveled and sharpened to provide a scraping edge, the outer side faces of the respective plates being disposed in forwardly diverging relationship to space the said outer side faces of said plates away from surfaces of the vertical walls of the gutter when in use, and arcuate shields mounted on said tube and covering the major portions of the respective slots, the outer ends of the shields being spaced inwardly from the outer ends of the slots.

CHARLES ANDREW GILBERT.
